United States Patent Office.

ALEXANDER McBRIDE AND WILLIAM P. McBRIDE, OF LOWELL,
MICHIGAN.

Letters Patent No. 93,632, dated August 10, 1869.

IMPROVED BED-BOTTOM.

The Schedule referred to in these Letters Patent and making part of the same.

To all whom it may concern:

Be it known that we, ALEXANDER McBRIDE and WILLIAM P. McBRIDE, of Lowell, in the county of Kent, and in the State of Michigan, have invented certain new and useful Improvements in Bed-Bottoms; and do hereby declare that the following is a full, clear, and exact description thereof, reference being had to the accompanying drawings, and to the letters of reference marked thereon, making a part of this specification.

The nature of our invention consists in the construction of a bed-bottom, and in the arrangement of the devices hereafter set forth and described.

Figure 1 is a perspective of our invention.

Figure 2 shows the manner in which the springs on the ends of the slats are fastened.

Figure 3 shows the manner in which the spiral springs are secured to the slats.

Letter A represents the frame of our bed-bottom, which is provided with the slats B.

To each end of these slats is secured a flat rubber spring, C, which passes over the top of the cross-piece D, and then is secured firmly in place by the pressure of the cross-piece against the end of the frame. The top of the cross-piece should be rounded off, so as to prevent the sharp edges from cutting the rubber, which they otherwise would, whenever there was the least weight brought to bear upon it.

Extending from one side to the other, in the middle of the slats, is the rubber band e, which prevents the slats from sagging too much at that point, or too much of a swinging side motion.

Placed upon top of the cross-piece F, in the bottom of frame A, are the spiral springs G, which support the slats in their centres.

A screw is passed down through the top of slats and rubber band e, and then has a-nut, n, secured upon its lower end, inside of the spiral spring, binding them all firmly together.

Upon the top of the cross-piece F, there is a flat rubber band, o, which forms a bed upon which the springs G rest.

Having thus described our invention,

What we claim, and desire to secure by Letters Patent, is—

The arrangement of the frame A, cross-pieces D and F, rubber bands e and o, nuts n, and springs C and G, when all are combined to form a bed-bottom, substantially as set forth.

In testimony that we claim the foregoing, we have hereunto set our hands, this 13th day of May, A. D. 1869.

ALEXANDER McBRIDE.

Witnesses: WILLIAM P. McBRIDE.
